UNITED STATES PATENT OFFICE.

HOWARD A. THOMAS AND ASA M. THOMAS, OF DRISCOLL, NORTH DAKOTA.

WELL-DRILLING MACHINE.

1,000,459.

Specification of Letters Patent. Patented Aug. 15, 1911.

Application filed May 12, 1910. Serial No. 560,967.

To all whom it may concern:

Be it known that we, HOWARD A. THOMAS and ASA M. THOMAS, citizens of the United States, residing at Driscoll, in the county of Burleigh, State of North Dakota, have invented a new and useful Well-Drilling Machine, of which the following is a specification.

This invention relates to well drilling apparatus in which the drilling tool is operated by raising it, and then permitting it to drop by its own weight, the drillings being removed by water, and it is the object of the invention to provide a simple, inexpensive, and efficient apparatus of this kind.

Another object of the invention is to provide an apparatus of the kind stated which can be readily hauled or transported from place to place, a wheeled supporting frame being provided on which the entire apparatus, including the pump for washing up the drillings, and the derrick, are carried, the latter being foldable.

The invention also has for its object to provide an apparatus which is easily controlled, the operating levers of the various clutches and other devices extending to one place, so as to be all within easy reach of the attendant.

Another object of the invention is to provide an improved device for operating the drill rope to impart a reciprocating movement to the drilling tool.

Other objects and advantages of the invention will be apparent when the same is better understood.

The invention is illustrated in the accompanying drawings, in which—

Figure 1 is a side elevation of the apparatus. Fig. 2 is an elevation of the means for operating the drill rope to impart a reciprocating movement to the drilling tool. Fig. 3 is an elevation of the brake mechanism of the drill rope drum. Fig. 4 is a plan view of the apparatus.

In the drawings, 1 denotes the frame of the machine, the same being mounted on the wheels 2, so that the apparatus may be readily transported from one place to another. On the rear end of the frame is supported a stub-derrick 3, to the top of which is pivoted as indicated at 4, the main derrick 5, carrying at the top a pulley 6 over which the drill rope 7 passes. The drill rope is connected to a suitable drilling tool, and is wound on a drum 8 loosely mounted on a

shaft 9 supported in bearings carried by the frame 1 near its rear end. A clutch 10 is provided for locking the drum on its shaft. This clutch is a collar which is splined on 60 the shaft 9 and has on each side a series of locking projections, one series of said projections being adapted to engage similar projections on a clutch member 11 fast on the drum. The other series of said projections is adapted to engage corresponding 65 projections on a clutch member 12 carrying a shaft 13. On this shaft is a crank arm 14, to which is connected a pitman 15, said pitman being also connected to the free end 70 of a lever 16 extending transversely of the apparatus, and pivoted at 17 to one side of the stub-derrick. The lever 16 swings in an inclined plane, and carries spaced sheaves 19. A strap 20 fastened to the lever, and 75 extending across the sheaves is provided, for securing said sheaves to the lever. The drill rope 7 extends from the drum 8 over one of the sheaves and then passes to the other sheave, under the same, and thence 80 upwardly to the pulley 6 at the top of the derrick 5.

The lever 16, and the parts carried thereby, are provided for imparting a reciprocating movement to the drilling tool. Upon 85 placing the clutch members 10 and 12 in locking engagement with each other, the shaft 13 is rotated from the shaft 9, and through the crank 14 and the pitman 15 swings the lever 16 up and down. This 90 movement of the lever alternately pulls the drill rope downwardly, and then releases the same, whereby the drill is raised, and then permitted by its own weight to drop. Upon 95 engaging the clutch member 10 with the clutch member 11 of the drum, the latter is locked on the shaft 9. A lever 21 is provided for operating the clutch member 10, said lever upon being swung in one direction engaging the said member with the 100 clutch member 11, and upon being swung in the opposite direction engaging the same with the clutch member 12. The drum is also provided with a brake mechanism which is shown in detail in Fig. 3. Said brake 105 mechanism comprises a band 22 fastened at one of its ends to a stand 23 mounted on one of the frame members 1, and passing around a friction rim 24 on the drum. The other end of the band is connected to a lever 25 110 fulcrumed at 26 on the stand 23. The friction rim is in the shape of a ring having

its inner periphery formed with ratchet teeth 27, which are engageable by a pawl 28 pivoted at 29 to one of the timbers of the stub-derrick 3, and connected by a link 30 5 to the lever 25. That end of the pawl which engages the ratchet teeth is offset so that it may engage the same. The connection between the lever and the pawl is such that the pawl will be disengaged from the ratchet 10 teeth when the lever 25 is swung in a direction to apply the brake, and when the lever is swung in the opposite direction to release the brake, the pawl is simultaneously engaged with the ratchet teeth. By the herein 15 described brake mechanism, the operator can readily control the drum, and check the descent of the drilling tool.

On the front end of the frame of the apparatus is mounted a motor 31 for driving 20 the several parts, said motor being, preferably, an internal combustion engine. On the crank shaft 32 of the motor is slidably mounted a friction disk 33 which is engaged by a friction wheel 34 mounted on a shaft 25 35 supported in bearings on the frame members 1. The friction disk 33 is mounted on the shaft 32 so as to rotate therewith, and as it is also slidably mounted on said shaft, it may be moved away out of contact with the 30 friction wheel 34, whereby the motor is disconnected from the parts to be driven. Any suitable means may be provided for operating 35 the friction disk 33 to disengage the same from the friction wheel 34, a lever 36 being shown which extends to the rear end of the apparatus. The friction wheel 34 is splined on the shaft 35 so that it may be moved closer to or farther away from the center of the friction disk, and thus change 40 the speed of the shaft 35. A suitable operating lever 37 for thus operating the friction wheel 34 is provided, said lever also extending to the rear end of the apparatus. The shaft 35 is connected by a belt 38, or 45 any other suitable form of gearing, to a shaft 39 journaled in bearings carried by the frame members 1. On this shaft is a pinion 40 which is in mesh with a spur gear 41 on the shaft 9. The motion of the motor 50 is therefore transmitted through the friction gears 33 and 34, and the belt 38 to the shaft 39, and through the gears 40 and 41 to the shaft 9, said shaft operating the drum 8 and the disk 13 as already described. The 55 shaft 39 also carries a balance wheel 42.

On each frame member 1 is mounted a pump cylinder 43, the pump outlets being connected to a pipe 44 to which the slush pipe 45 is connected, the latter pipe being 60 connected in the ordinary manner to the drill rod for the purpose of washing up the drillings, as usual.

The two pumps are driven from the shaft

39, said shaft carrying a sprocket wheel 46 which is connected by a chain 47 to a sprocket wheel 48 mounted on a shaft 49 65 journaled in suitable bearings on the frame members 1. Any other form of gearing between the shafts 39 and 49 may be provided. The shaft 49 is fitted at its ends with crank 70 disks 50 to which are connected the pitmen 51 of the pump plungers. The sprocket wheel 46 is loose on the shaft 39, and is formed with a clutch member 52 adapted to be engaged by a clutch member 53 mounted 75 on the shaft 39, so as to rotate therewith, said clutch member 53 being also slidable on the shaft so that it may be brought into engagement with the clutch member 52, and when thus engaged, the motion of the shaft 80 39 is transmitted by the sprocket and chain gearing described, to the shaft 49. The clutch member 53 is provided with an operating lever 54.

The levers 21, 25, 36, 37 and 54 all extend 85 to the rear end of the apparatus so as to be within easy reach of the operator. The apparatus can be instantly stopped without stopping the motor, upon operating the lever 36 so as to disengage the friction disk 33 90 from the friction wheel 34, and the speed is also readily controlled upon adjusting the friction wheel on the friction disk by means of the lever 37.

The derrick 5 is pivotally connected to the 95 stub-derrick 3 in order that it may be folded down on top of a supporting frame 54 as shown by dotted lines in Fig. 1, so that the apparatus may be readily hauled about from one place to another.

What is claimed is:

A drilling apparatus comprising a frame, a driven shaft journaled thereon, a pump mounted thereon, means for operatively connecting the pump with the driven shaft, a second shaft journaled upon the frame and operatively connected with the driven shaft, a drum loosely mounted upon the last mentioned shaft, a drill rope arranged to wind upon the said drum, means for reciprocating the drill rope, a double clutch member mounted on the second mentioned shaft and movable to operate the drum or the drill rope reciprocating means repeatedly or alternately from the second mentioned shaft and a single lever for shifting said clutch member.

In testimony that we claim the foregoing as our own, we have hereto affixed our signatures in the presence of two witnesses.
